UNITED STATES PATENT OFFICE.

JULIUS A. LANDSBERGER, OF ALAMEDA, CALIFORNIA, ASSIGNOR TO
HERMETIC CLOSURE COMPANY, OF CHICAGO, ILLINOIS.

VACUUM CAN-SEALING MACHINE.

No. 831,527.

Specification of Letters Patent.

Patented Sept. 18, 1906.

Application filed April 20, 1903. Serial No. 153,525.

To all whom it may concern:

Be it known that I, JULIUS A. LANDSBERGER, a citizen of the United States, residing at Alameda, in the county of Alameda and State of California, have invented a certain new and useful Improvement in Vacuum Can-Sealing Machines, of which the following is a specification.

It is a common practice in one form of "sealing cans," under which term is included cans, jars, and receptacles generally, to employ a vacuum-seal which ordinarily and in a general way is obtained by placing the can, with the cover and packing held in place by a spring-clamp, in a receiver from which the air is first exhausted and then readmitted. The cover by reason of the resiliency of the spring-clamps acts, in effect, as a valve, enabling the air to be removed from the can as the receiver is exhausted and preventing the reentrance of the air into the can when the air is readmitted, with the result that the cover is forced into tight contact by the pressure of the atmosphere, making an effectual hermetic seal. This method of sealing is objectionable in regard to the production of a perfect and uniform vacuum in each instance, the objection arising from the fact that with a heavy spring there must necessarily be a loss of vacuum equivalent to the pressure exerted by the spring-clamp, which would force the cover to place prior to the creation of a vacuum within the can corresponding to the vacuum in the receiver, and with a light spring for the clamp a comparatively higher or lower vacuum in the can than that in the receiver will be obtained, depending on the uniformity of the gasket and of the sealing-surface of the can and cover, both of which directly affect the valve action of the cover. The result with a heavy spring would be a minimum loss of vacuum, dependent on the strength of the spring used, and with a light spring the resultant effect would be erratic and varying with the relationship of the members one to the other.

The primary object of my invention is to insure the same degree of vacuum within the can as that obtainable in the receiver, employing for this purpose mechanically-operated means which will at the same time enable the sealing of the can to be quickly and economically attained; to enable the air to be exhausted from the can without

sure applied to the cover of the can, so that 55 the cover practically offers no obstruction to the free exit of the air from within the can, and when the air is exhausted from the can to then force the cover into tight contact by mechanical means located within the receiver 60 and operated from the exterior of the receiver; to enable a cover with which is employed a solid compressible packing to have initially applied thereto a pressure materially greater than that of the atmosphere to force 65 the gasket or packing to shape itself in conformity to and with any irregularity of the can or cover, so that when the air is readmitted to the receiver a perfect air-tight joint is formed; to employ a mechanical presser located within the receiver and arranged to engage with and initially force down the cover and actuate it mechanically by means operative outside of the receiver; to govern and control the movements of the presser in applying 70 the cover to the can by means operating to apply the pressure at the particular moment and for whatever duration of time may be desired, by which the principle of the invention is applicable to automatic machines generally; to 75 govern and control the movements of the presser within the receiver by a cam actuated by a foot or hand lever and so arranged and operated as to apply great power with the application of but little force on the lever or 80 other actuating device; to increase the efficiency of the devices for use with a composition gasket or packing by arranging a plate 85 electrically heated or otherwise and operating to soften the gasket or packing, so that 90 with the readmission of air into the receiver the softened gasket or packing will be pressed closely against the can and cover; to regulate and equalize the application of the pressure from the mechanically-actuated presser 95 on the cover of the can by interposing a resistance-spring, which can be regulated so as to control the pressure between the rod applying the power and the plunger or presser-head which applies the pressure to the cover, 100 the spring having a fixed tension by which the application of a too great pressure or a more positive pressure than is requisite is prevented, which pressure might tend to break or deform the can or cover; to render 105 the appliance suitable for different heights of cans by means of an adjustable plate raised

ed stem operated from the exterior of the receiver; to furnish a supporting-plate and a presser-head both located within the receiver and between which the can is placed 5 and to so arrange the plate and the head as to allow the cover to rise sufficiently for permitting the air to escape freely from the can without any liability of displacing the cover; to maintain the relative movement of the supporting-plate and the head down to a minimum 10 in order to apply the proper pressure to the cover at the time and during the period required to force the cover to place, and to automatically open and close the valve for controlling the production of the vacuum within 15 the receiver and readmitting air into the receiver.

The accompanying drawings show machines having embodied therein the essential features of the invention, the machine shown 20 being of a type operated by hand or foot levers as regards the movements of the mechanically-actuated presser within the receiver for applying force to set the cover before readmitting air into the receiver; but 25 it is to be understood that the essential features of the invention can be applied to and are operative with power-actuated machines.

30 In the drawings, Figure 1 is a sectional elevation showing a simple form of construction and arrangement of the several elements entering into the machine as a whole; Fig. 2, a sectional elevation showing a modification in the arrangement of the plate on which the bottom of the can rests and the presser-head for forcing the cover tightly against the packing on the can after the vacuum has been produced in the can; Fig. 3, a 35 side elevation of the cam and lever for forcing down the presser-head in the construction shown in Fig. 1; Fig. 4, a side elevation of a modified construction, showing means for operating the controlling-valve for creating a vacuum and readmitting air, one of the 40 means being carried by the door for closing the receiver, and showing also a controlling-spring against which the operating-cam acts; Fig. 5, a sectional elevation of the construction 45 and arrangement shown in Fig. 4; Fig. 6, a front elevation of the construction and arrangement shown in Fig. 4; Fig. 7, a side elevation of the receiver with the standard or support therefor in section, showing a 50 modification of the construction and arrangement of means for automatically opening and closing the valve controlling the production of a vacuum and the readmission of air into the receiver, said means being operative 55 from a foot lever or treadle which actuates the cam by which the presser-head is advanced, and showing also means for automatically opening and closing the door from the 60 movements of the foot lever or treadle; Fig. 65 8, a sectional elevation of the receiver shown

in Fig. 7 with the means for operating the controlling-valve for the vacuum and for readmitting air into the receiver; Fig. 9, a detail in cross-section of the valve for creating a vacuum and readmitting air into the receiver 70 with the reciprocating rod of Fig. 7 by which the valve is turned; Fig. 10, an elevation of the head shown in Fig. 8; Fig. 11, a sectional elevation of the head of Fig. 10; Fig. 12, a detail showing the cap having 75 therein one-half of the socket for the ball of the threaded stem of Figs. 10 and 11; and Fig. 13, a plan view showing the construction of resistance-coil or rheostat.

The receiver or vacuum-box A is made of 80 any suitable material and is constructed so as to be perfectly air-tight and has on one side an opening a for placing within and withdrawing from the vacuum-chamber of the receiver or box a can and its cover. One side 85 of the box has a cover A' with a packing a' to encircle the opening a and insure a tight joint around the opening when the cover is closed, and, as shown, the cover is attached by a suitable hinge a' to the top of the box; but the 90 cover could be otherwise hinged or attached. A plate B, as shown in Fig. 1, is located within the chamber of and adjacent to the bottom of the box and is of a dimension to receive a can thereon and furnish a support for the 95 can. The plate B, as shown, is carried by a screw-threaded stem B', passing through a suitable stuffing-box b, so as to make an air-tight joint around the stem, and the stem, as shown, has a hand-wheel b', by means of 100 which it can be turned to raise and lower the plate and locate the same in proper relation to the presser-head for the length of can, and thus enable cans of different heights to be placed between the presser-head and plate 105 and operated upon in the vacuum-box.

The presser-head C or the head for pressing down the cover on the top of the can is constructed, as shown in Fig. 1, so as to be heated and has on its under side a circular rim or rib c to engage the cover and through the heat applied to the presser-head soften a composition packing within the cover to an extent sufficient to insure the compression of the packing and the firm seating thereof 110 around the edge of the can and against the under face of the cover so as to fill any irregularities between the can and cover. The presser-head C is carried by a support D, having, as shown, a side wall d, threaded onto 115 the lower end of which is an angle-strip d', the horizontal portion of which forms a rest for the presser-head when in the support, and the angle-strip can be raised or lowered through its screw-threaded attachment to 120 furnish a slight adjustment vertically of the presser-head for proper action in pressing on the cover.

The support D for the presser-head is attached, as shown in Fig. 1, to the lower end of 130

a stem or rod E by means of an outer nut d^2 and an inner nut d^3 ; but other attaching means can be employed. The inner nut d^3 , as shown, engages or contacts an abutment c' 5 on the presser-head to force the presser-head down and, as shown, between the presser-head and its support D is a resistance-spring D', having sufficient force to furnish a cushion and prevent damaging, breaking, or 10 otherwise injuring the can and cover from any quick, sudden, or hard or over depression of the presser-head. The stem E extends through a stuffing-box e, which forms a tight joint around the stem, and the upper end of 15 the stem E has thereon a head e', between which and the stuffing-box is a coiled spring E', which serves to return the support and the presser-head carried thereby to normal position after each operation of applying a 20 cap or cover to a can.

A cam F is mounted on a shaft or rod f, supported in standards F', extending up from the top of the vacuum-box, and this cam F has a circular acting face f' and an eccentric acting face f'' for the face f' to engage 25 with the head e' when the parts are normal and for the eccentric acting face f'' to engage with the head e' and force down the presser-head, and, if desired, the eccentric face f'' 30 after the point where a downward movement of the presser-head should cease can be formed on a true circle, so that a further movement of the cam will not force the presser-head against the cap or cover. The cam in the 35 construction of Fig. 1 is turned by a hand-lever F'', but could be turned by any other suitable means, and the cam should be so formed and should be under such control as to apply great power with the exertion of but 40 little force and to apply the pressure on the cover at the particular moment and for whatever duration of time may be required to seat the cover firmly in place and hold it there until the air is again readmitted to the vacuum-chamber. 45

A pipe G, having a shut-off valve g, is entered into the vacuum-box in communication with the chamber thereof, and from the valve g a suitable pipe leads to a vacuum-pump or an exhausted chamber, (not shown,) so that when the door A' is closed a vacuum can be created in the vacuum-box and the can. A pipe H, having a shut-off valve h, is entered into the vacuum-box in communication 50 with the chamber thereof, and leading from the valve h is a nozzle or pipe i in communication with outside air, so that at the completion of the vacuum and when the cover has been applied by the presser-head 55 air can be admitted to the chamber with the presser-head holding on the can-cover by closing the valve g and opening the valve h for the admitted air to operate and by its own pressure hold the cap firmly on the can, owing to the vacuum in the can, as usual, and

in creating a vacuum it will be understood that the valve h is to be closed. The arrangement shown has conductors I and I' leading from a dynamo or other source of electric energy, (not shown,) and these conductors are connected by wires i and i', respectively, with the binding-post of a resistance-coil or rheostat in the presser-head C for the heat produced from the passage of the current through the resistance-coil or 75 rheostat to heat the presser-head sufficiently to soften the packing, if so desired.

The resistance-coil or rheostat employed is shown in one form of construction in Fig. 13. The wire I² of the resistance-coil or 80 rheostat is bent zigzag or sinuous, so as to run back and forth in a parallel series concentrically with the circumference of the presser-head, and in order to prevent the wire of the resistance-coil or rheostat coming 85 in contact with the metal of the head, which would short-circuit the current, the wires are embedded in a non-conductor i², which may be plaster or other suitable material. One end of the zigzag wire of the resistance-coil 90 or rheostat is attached by an insulated wire i³ with a binding-post i⁴, to which is connected one of the wires i or i', and the other end of the zigzag wire of the resistance-coil or rheostat is connected by an insulated wire i⁵ 95 with a binding-post i⁶, to which is attached the other wire i or i', by which the conductors I and I' are connected with the resistance-coil or rheostat. It will be understood that the fine wire of the resistance-coil or 100 rheostat is heated, as usual, by the resistance offered to the electric current, and this heat in turn is transmitted to the non-conducting plaster in which the wire is embedded, and the plaster in turn contributes the necessary 105 heat to the head for softening the gasket, as hereinbefore described.

The operation with the construction of Fig. 1 is as follows: The plate B is raised or lowered to properly adjust the space between 110 the plate and presser-head for the height of the can. A can when the door A' is open is placed on the plate and the door A' closed, tightly sealing the chamber of the vacuum-box. A vacuum is then created in the vacuum-chamber and at the same time in the can L, the cover L' resting free on the top of the can, so as to rise for the air to escape from the can. At the completion of the vacuum the cam or eccentric F is turned for its eccentric acting face f'' to engage the head e' and force down the stem E, pressing the head C against the cover and carrying the cover down to contact at all points with the packing l and force the packing closely against 115 the top of the can, making a tight sealing of the can by the packing and the cap or cover, the cover shown having a depending flange l' to slip over the top of the can and hold the packing in place while the cover and packing 120 125 130

is being pressed into position on the top of the can. When the cap or cover has been seated or carried down to the extent required for the production of a tight joint and with the presser-head still engaged with the cover, air is admitted to the chamber of the vacuum-box, breaking the vacuum for the pressure of the admitted air to vacuum-seal and tightly hold the cap or cover in place, after which the presser-head can be raised and the can withdrawn with the certainty that the cover will remain on the can and the can will be perfectly sealed. This machine enables a loose or slip cover to be applied to a can by and through mechanical pressure, the force for doing which is exerted from outside of the vacuum-box, and the cap or cover is applied without any impingement or binding of the flange of the cap or cover against the body of the can and with the assurance that the cover will be held firmly in place and vacuum-sealed onto the can.

The construction shown in Fig. 2 has the plate B, forming the shelf or table which carries the can, mounted on the end of a sliding stem B², which stem passes through the stuffing-box b, and between the stuffing-box and a pin or flange b² is a coiled spring b³, which serves to hold the lower end of the stem against the acting face of an eccentric or cam J, mounted on a journal pin or pivot j and operated by a foot-lever J', so that by pressing down on the tread of the foot-lever the shelf or table can be raised to force the cover against a presser-head for the contact to press the cover with the packing therein tightly against the top of the can, so as to make a tight joint and seal the can, as described, for the construction of Fig. 1. The presser-head C' in the construction shown in Fig. 2 is formed of a plate c² and a cushion or yielding section c³, against which the cover of the can is brought into contact with the raising of the shelf or table. The presser-head C' in the construction of Fig. 2 is carried by a screw-threaded stem E², passing through a stuffing-box e and having a hand-wheel e², by means of which the stem can be turned to raise and lower the presser-head and bring it in proper relation to the movement of the can from the plate B to insure the cover being pressed down properly. The presser-head and the plate constitute, in effect, the two members of a clamp, one of which is to be movable to engage the cover and press it to place on the can and the other one of which can be adjustable or stationary so long as the arrangement is such as to enable the movable member to be actuated outside of the vacuum-box and supply mechanical pressure to seat the cover. As shown in Fig. 1, the presser-head is movable and the plate B is held in a fixed position after it is adjusted, and, as shown in Fig. 2, the presser-head is held in a fixed position

after it is adjusted and the plate with the 65 can thereon is movable to press the cover to place on the can; but the operation of the devices in either form of construction is the same so far as relates to the creating of a vacuum, 70 pressing and holding the cover on the can by mechanical pressure, breaking the vacuum, and removing the can are concerned.

The construction shown in Figs. 4, 5, and 6 so far as relates to the general construction and arrangement of the means for obtaining 75 a mechanical pressure on the cover of the can is the same as the construction shown in Fig. 1, except as follows: The door A' is hinged at the bottom instead of at the top, and extending downwardly from the hinge is a rod a³, 80 carrying a counterbalance-weight a⁴ for the door, so as to make, in effect, the door a balanced one. The cam F works against a cross-head E², having at each end a slide e², moving on the standards or uprights F', and the cross-head has at its center a boss e³, encircled by a spring E³, the lower end of which surrounds the upper end of the stem E and contacts with an adjustable nut e⁴ on the thread of the stem, which nut when adjusted is held in 90 place by a lock-nut e⁵, so that by adjusting the nut e⁴ the spring E³ can be more or less compressed, so as to furnish a resistance and a cushioning effect against operating the presser-head too quickly or with too hard a 95 pressure and create damage. The door A' has pivotally mounted thereon a shaft M, held in position by ears m and encircled between the ears by a coil-spring M', one end of which is fixedly attached to the shaft and the other end of which is attached to the door for the spring to have a back action or throw and return the shaft to the normal position. (Shown in Fig. 4.) The shaft has an arm m' with a lateral extension m², which lies clear of 100 the plane of the edge of the door. The extension m² of the arm of the shaft is arranged to engage an arm N, fixedly attached to a stem g³ of a controlling-valve hereinafter described, and the arm N has an extension n, to the 110 outer end of which is attached the end of a pull-spring n', the other end of which is attached to the side of the vacuum-box, so that with the depression of the arm N by the engagement therewith of the arm of the shaft 115 M the valve will be opened for the creation of a vacuum within the chamber of the box and will remain open as long as the arm of the shaft M is maintained in engagement to depress the arm N, and with the release of 120 the engagement the pull-spring, which has been extended, will act and close the valve against the vacuum and open the valve to admit air to the vacuum-chamber. This construction places the operation of the controlling-valve under the control of the operator in closing and opening the door, and with 125 the door closed the movement of the shaft M

- is continued forwardly, pushing down the arm N and opening the valve for the creation of a vacuum.
- The valve is illustrated in detail in Fig. 9. 5 This valve G' is a three-way valve and consists of a shell or casing g', a cylindrical plug g² within the casing, the plug having a cross-passage g³, running from which is a passage g⁴, leading to the exterior of the plug. Entered 10 into a boss on the shell of the valve is a short tube G², which leads into the vacuum-chamber of the box, and a pipe G³ is entered into a boss on the opposite side of the valve shell or casing, and this pipe is connected by a hose 15 or other suitable means with an exhausted chamber or a vacuum-pump. The passage g³ when the plug of the valve is in the position shown in Fig. 9, which is the normal position, communicates with a port g⁵ in the 20 wall of the valve, and the passage g⁴ communicates with a port g⁶ in line with the pipe G² for admitting atmospheric air into the vacuum-chamber to break the vacuum. The 25 downward movement of the arm N turns the passages g³ and g⁴ out of communication with the ports g⁵ and g⁶, respectively, and brings the passage g³ into communication with the ports g⁶ and g⁷, the latter of which is in line with the pipe G³, establishing communication 30 between the chamber of the vacuum-box and the exhausted chamber or vacuum-pump to create a vacuum in the chamber of the vacuum-box when the door A' is closed. The construction of Figs. 4, 5, and 6 enables 35 the valve G' to be actuated when the door A' is closed by causing the arm of the shaft M to depress the arm N and turn the plug of the valve to establish communication for creating a vacuum in the box, and with the release 40 of the arm of the shaft by the operator the spring n' returns the arm N to normal position, admitting air to the vacuum-chamber. This construction and arrangement makes the operation of the controlling-valve for creating 45 a vacuum and admitting air dependent on the closing of the door and the will of the operator, and with this construction a single pipe is all that is required for both creating a vacuum and breaking a vacuum.
- 50 The construction shown in Figs. 7 and 8 has the movable member of the clamp in the plate B as in the construction of Fig. 2. The plate is carried by a stem B³, around which is a coiled spring b³, located between the stuffing-box and an adjusting-nut b⁴, contacted by a lock-nut b⁵, both the nuts operating on the threaded end of the stem B³, so that by adjusting the nut more or less force can be given to the spring b³ in returning the plate B 55 to normal position. The plate B is raised by the upward movement of a sliding stem B⁴, the lower end of which is engaged by the acting face of the cam J, and between the stems B³ and B⁴ is a cushioning-spring b⁶, engaged
- at its upper end with the nut b⁵ and engaged 65 at its lower end with an adjusting-nut b⁷, held when adjusted by a lock-nut b⁸, both nuts operating on the threaded end of the stem B⁴, so that by adjusting the nut b⁷ the necessary resistance can be given to the spring b⁶ for the prevention of an excess of pressure. The sliding stem B⁴ is supported in guides b⁹, extending out from a standard O, on which the vacuum-box is mounted in the arrangement shown. The presser-head C' of Fig. 8 70 75 in order to allow the head to be forced into contact with the cover of the can has its screw-threaded stem E² terminating in a ball e³, entered into a socket e⁶, one portion of which is formed in the top plate of a cap C², 80 such top plate having therein a slot c⁴ leading from its periphery to the half-socket e⁶ in its under face, as shown in Fig. 12. The other half of the socket e⁶ is formed in the upper face of a boss C³, extending up from the 85 top of the presser-head C', as shown in Fig. 11, and the cap C² is locked to the boss C³ by a bolt or screw c⁵ passing through the side wall of the cap and entered into the boss. This ball-and-socket connection of the actuating-stem E² with the presser-head C' enables the threaded stem to be rotated in either direction without rotating the presser-head, so that in advancing and receding the presser-head the connection of the electric- 90 95 current conductors I and I' with the resistance coil or rheostat is non-affected by the movements of the presser-head. The construction of Figs. 7 and 8 employs means for automatically closing the door and opening 100 the controlling-valve G' to create a vacuum with the raising of the shelf to bring the jar into position. The means shown consists of of a rod K, having in its body a slot k, into which projects a pin k' on the end of an arm K', attached to the door at its hinging-point. The body of the stem at the slot K is surrounded by a spring k², the lower end of which engages the end of the arm K' and the upper end of which engages an adjusting- 105 nut k³, held in place when adjusted by a lock-nut k⁴, both nuts operating on a thread of the stem, so that by adjusting the nut k³ the required amount of force will be exerted by the spring for the downward movement of the 110 rod K, which is attached to the foot-lever J', to cause the spring to act on the arm K' and close the door, the spring allowing of a continued downward movement of the rod K after the door is fully closed for such downward movement to open the valve G' for the 115 creation of a vacuum.
- The upper end of the rod K has a spring-fork k⁵, with a slot k⁶, which slot receives the arm N, which operates the plug of the valve. 120 The downward movement of the rod K causes the shoulders at the outer end of the slot k⁶ to engage the arm N and turn the 125

valve into position for the passage g^3 to be in communication with the ports g^6 and g^7 , and the rod K can be carried down sufficiently far for the forked end k^5 to slip off the end of the arm N, when the spring n' will act, returning the arm N to normal position and opening the valve G' to admit outside air to the vacuum-chamber and break the vacuum. This construction makes the closing of the door and the actuating of the controlling-valve for creating and breaking a vacuum automatic at the will of the operator through the depression of the lever J', by which the cam J is operated to raise the plate B, as with the initial upward movement of the plate the rod K, through the spring k^2 , will depress the arm K' and close the door and with the further movement upward of the plate B with the door closed the arm N will be depressed to open the valve for creating a vacuum before the limit of upward movement of the plate is reached, by which the cover will be pressed onto the can from the engagement with the presser-plate, and when the cover is in place the arm N has been carried down to a point where its end will be passed by the end of the rod K in the further descent of the rod K, releasing the arm N from its engagement with the rod K and allowing the spring to act and return the arm N to normal position and admit air into the chamber of the vacuum-box to break the vacuum, so that with the release of the foot-lever the door can open and the jar, with the cover thereon vacuum-sealed, can be removed. The spring-fork at the upper end of the rod K opens for the arm N to pass into the slot k^6 as the foot-lever and the rod return to normal position.

It will thus be seen that with the construction of the machine or apparatus of the present invention a uniformity of operation is secured and the same degree of vacuum within the can is attained as is obtainable in the vacuum-box, enabling the cans to be vacuum-sealed quickly and economically by mechanical pressure operative from the exterior of the box; that the air is exhausted from the vacuum box or receiver before any pressure is applied on the cover of the can; that the cover of the can does not offer any obstruction to the free exit of the air from within the can; that mechanical pressure is applied to close the can after the vacuum has been created therein, and this pressure is maintained until after the atmosphere has been admitted into the vacuum box or receiver to break the vacuum; that the application of the pressure is mechanically obtained and is not dependent on the admission of the atmosphere to force the cover into contact with the can before readmitting the atmosphere into the top of the vacuum box or receiver proper; that a solid compressible packing can be softened, thereby insuring the close fitting of the packing or gasket to the cover and can and also enabling

the packing or gasket to shape itself so as to conform with any irregularities of the can or cover; that the control of the valve is placed under the will of the operator and is dependent upon the closing of the door of the vacuum-box; that the application of the mechanical pressure is had from the exterior of the box and is under controlling means, by which a sufficiency of pressure is all that is obtainable for use in setting the cover onto the can; that the pressure can be applied at the time required and for whatever duration of time may be necessary and no more; that a cushioning action is secured by which overpressure that might create damage will be overcome and prevented; that cans of different heights can be operated upon by simply adjusting the parts of the clamp to suit the height of the can; that the members of the clamp can be brought into operative relation for the point of pressure to be in close proximity to the cover during the exhausting process, allowing the cover to rise sufficiently, however, for the escape of the air freely from the can and at the same time preventing the cover from rising so high as to become displaced, leaving a minimum of movement to close the cover onto the can by the application of the mechanical pressure at the proper time; that the relative movements of the members of the clamp in their relation one to the other can be maintained at a minimum and can be changed at pleasure, and that the operation of the several parts can be made automatic in the matter of causing the members of the clamp to approach each other, closing the door and operating the valve controlling the production of a vacuum and the admission of air to break the vacuum. All these features are found in the construction of the present machine and are desirable in the operation of vacuum can-sealing machines.

What I regard as new, and desire to secure by Letters Patent, is—

1. In a vacuum can-sealing machine, the combination with a vacuum-box having a chamber for the placement therein of a can having a loose cover to be vacuum-sealed on the can, of a presser-head within the chamber arranged to engage, press down, and apply the cover on the can, a stem carrying the presser-head and extending through the box, a cam engaging with the end of the stem, a spring between the outer end of the stem and the box and encircling the stem, and means for turning the cam a predetermined distance to advance the head in applying the cover to the can, substantially as described.
2. In an apparatus for sealing receptacles in vacuo, a vacuum-chamber, a swinging door therefor, a valve for controlling the exhaustion of air from and admission of air to the said chamber, and means, carried by the door for operating said valve.

3. In an apparatus for sealing receptacles *in vacuo*, a vacuum-chamber, a swinging door therefor, a valve for controlling the exhaustion of air from and admission of air to the said chamber and means, carried by the door, for controlling said door and operating said valve.
4. In an apparatus for sealing receptacles *in vacuo*, a vacuum-chamber, a door for the same, a valve for exhausting and readmitting air from and to the same, a lever for controlling the door, and a lever for opening the valve; the valve-opening lever being operated by the door-controlling lever.
5. In an apparatus for sealing receptacles *in vacuo*, a vacuum-chamber, a door for the same, a valve for exhausting and readmitting air from and to the same, a handle carried by the door for controlling the same, and a valve-opening lever operated by said handle.
6. In an apparatus for sealing receptacles *in vacuo*, a vacuum-chamber, a door for the same, a valve for exhausting and readmitting air from and to the same, a valve-lever, and a handle journaled on the door for closing and opening said door, and adapted, after im-
- parting the closing movement to said door to operate said valve.
7. In an apparatus for sealing receptacles *in vacuo*, a vacuum-chamber, a door for the same, a valve for exhausting and readmitting the air from and to the same, a valve-lever, a handle journaled on the door for closing and opening said door and having a movement of its own independently of the door; whereby after imparting a closing movement to the door the said handle can continue its movement and operate the valve-lever.
8. In an apparatus for sealing receptacles *in vacuo*, a vacuum-chamber, a door for the same, a valve for exhausting and readmitting air from and to the same, a valve-lever movable in one direction for opening said valve and having a spring for moving it automatically in the other direction for closing said valve, a handle on the door for operating both said door and said valve-lever, and a spring for retracting said handle.

JULIUS A. LANDSBERGER.
